CLAIM

The ornamental design for a grille for air purifier, as shown and described.

DESCRIPTION

FIG. 1 is a front perspective view of a grille for air purifier showing our new design according to a first embodiment; FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is an enlarged view of the encircled portion in FIG. 1;

FIG. 9 is an enlarged view of the encircled portion in FIG. 7;

FIG. 10 is a front perspective view of a grille for air purifier showing our new design according to a second embodiment; FIG. 11 is a front view thereof;

FIG. 12 is a rear view thereof;

FIG. 13 is a left-side view thereof;

FIG. 14 is a right-side view thereof;

FIG. 15 is a top view thereof;

FIG. 16 is a bottom view thereof;

FIG. 17 is an enlarged view of the encircled portion in FIG. 10; and,

FIG. 18 is an enlarged view of the encircled portion in FIG. 16.

The evenly-dashed broken lines in the figures depict portions of the grille for air purifier which form no part of the claimed design.

The dot-dot-dash broken lines encircling portions of the claimed design that are illustrated in enlargements form no part of the claimed design.
